US0D1113886S

(12) **United States Design Patent** (10) **Patent No.:** **US D1,113,886 S**
(45) **Date of Patent:** **** Feb. 17, 2026**

(54) **GIMBAL**

(71) Applicant: **Autel Robotics Co., Ltd.**, Guangdong (CN)

(72) Inventors: **Jianlong Liao**, Guangdong (CN); **Yuelong Liao**, Guangdong (CN)

(73) Assignee: **Autel Robotics Co., Ltd.**, Guangdong (CN)

(**) Term: **15 Years**

(21) Appl. No.: **29/881,391**

(22) Filed: **Dec. 30, 2022**

(51) **LOC (15) Cl.** **16-06**

(52) **U.S. Cl.**

USPC **D16/218**

(58) **Field of Classification Search**

USPC D14/239, 217; D16/202, 218, 219, 227, D16/238, 239, 240, 207, 203, 201, 210

(57) **CLAIM**

The ornamental design for a gimbal as shown and described.

DESCRIPTION

FIG. 1 is a front, right and top perspective view of a gimbal, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the gimbal that form no part of the claimed design.

1 Claim, 8 Drawing Sheets
